(57) **CLAIM**

I claim the ornamental design for an artificial fish eye, as shown and described.

DESCRIPTION

FIG. 1 is a top plan view of an artificial fish eye of this invention;

FIG. 2 is a bottom plan view of the invention and depicting a notch therein;

FIG. 3 is a front elevational view of the present invention;

FIG. 4 is a side elevational view of the present invention, the opposite side being a mirror image thereof; and,

FIG. 5 is a rear elevational view of the present invention. The stippling depicted in the accompanying drawings depicts surface contour only and does not depict any texture, color, shading or other characteristic.

1 Claim, 1 Drawing Sheet

FIG. 4

FIG. 1

FIG. 5

FIG. 3

FIG. 2

UNITED STATES PATENT AND TRADEMARK OFFICE
CERTIFICATE OF CORRECTION

PATENT NO. : Des. 529,240 S
APPLICATION NO. : 29/226302
DATED : September 26, 2006
INVENTOR(S) : Antonio R. Alfaro

Page 1 of 1

It is certified that error appears in the above-identified patent and that said Letters Patent is hereby corrected as shown below:

<Title Page>

Item (54) should read -- ARTIFICIAL BOAR EYE --.

Item (57) Claim should read -- 1 claim the ornamental design for an artificial boar eye, as shown and described. --

In Description, a sentence starting from Line 1 should read --FIG. 1 is a top plan view of an artificial boar eye of this invention; --

Signed and Sealed this

Twelfth Day of December, 2006

A handwritten signature in black ink, appearing to read "Jon W. Dudas". The signature is written in a cursive style with a large, stylized "J" and "W".
